United States Patent Office

Des. 215,861
Patented Nov. 4, 1969

215,861

HAND DRIVEN WHEELED VEHICLE

Calvin C. Cook, Erie, Pa., assignor to Louis Marx &
Company Inc., a corporation of New York

Filed Jan. 29, 1969, Ser. No. 15,559

Term of patent 14 years

Int. Cl. D21—02

U.S. Cl. D34—15

FIG. 1

FIG. 2

FIG. 1 is a top plan view of a hand driven wheeled vehicle embodying my new design;

FIG. 2 is a side elevational view thereof;

FIG. 3 is a bottom plan view thereof;

FIG. 4 is a front end view thereof; and

FIG. 5 is a rear end view thereof.

I claim:

The ornamental design for a hand driven wheeled vehicle, as shown.
